US00D881917S

(12) **United States Design Patent** (10) Patent No.: **US D881,917 S**
(45) Date of Patent: **** Apr. 21, 2020**

(54) **COMPUTER DISPLAY WITH HOME SCREEN INTERFACE**

(71) Applicant: **DEKA Products Limited Partnership**, Manchester, NH (US)

(72) Inventors: **Allison E. Lepine**, Concord, NH (US); **Constance D. Pitenis**, Hooksett, NH (US); **Eric N. Sabin**, Manchester, NH (US)

(73) Assignee: **DEKA Products Limited Partnership**, Manchester, NH (US)

(**) Term: **15 Years**

(21) Appl. No.: **29/661,806**

(22) Filed: **Aug. 30, 2018**

Related U.S. Application Data

(62) Division of application No. 29/579,660, filed on Sep. 30, 2016, now Pat. No. Des. 830,384.

(51) **LOC (12) Cl.** **14-04**

CLAIM

The ornamental design for a computer display with home screen interface, as shown and described.

DESCRIPTION

The sole FIGURE is the computer display with home screen interface, showing our new design.

The outer edge of the portion of the display screen is understood to be congruent with the outer edge of the computer display with home screen interface.

1 Claim, 1 Drawing Sheet
